DANIEL M. TUTTLE, OF CANASTOTA, NEW YORK.

GAS-ENGINE.

No. 840,178.

Specification of Letters Patent.

Patented Jan. 1, 1907.

Application filed May 25, 1905. Serial No. 262,294.

To all whom it may concern:

Be it known that I, DANIEL M. TUTTLE, of Canastota, in the county of Madison, in the State of New York, have invented new and useful Improvements in Gas-Engines, of which the following, taken in connection with the accompanying drawings, is a full, clear, and exact description.

This invention relates to improvements in gas-engines of the two-cycle type, and refers more particularly to the means for introducing the hydrocarbon liquid directly into the explosion-chamber without entering the crank-chamber, so as to avoid any liability of back firing or explosion of the mixture in the crank-chamber.

The primary object, therefore, of my invention is to provide means controlled by the compression of air in the crank-chamber for forcing the hydrocarbon liquid directly into the explosion-chamber either at the base or top without causing it to enter the crank-chamber.

Another object is to cause the mixture of the hydrocarbon liquid with a suitable amount of the air at the point of entrance to the explosion-chamber, thereby obviating any necessity for vaporizers or auxiliary mixing devices.

A further object is to automatically regulate the quantity of liquid hydrocarbon entering the explosion-chamber according to the load or work required or performed.

It will be observed, however, from the following description that the essential purpose of the invention is to prevent the formation of any explosive mixture and liability of explosion of the explosive gases within the crank-chamber and to regulate the volume of explosive charge to harmonize with the load or work required.

Other objects relating to the specific details of the mechanism for carrying out the foregoing objects will be brought out in the following description.

In the drawings, Figure 1 is a transverse sectional view of a single-cylinder two-cycle gas engine embodying the features of my invention. Fig. 2 is an enlarged sectional view taken on line 2-2, Fig. 1.

In demonstrating the practicability of my invention I have shown an ordinary gas-engine consisting of a cylinder 1 and crank-case 2, in which are movable, respectively, a piston 3 and crank 4, the latter being connected to the piston by means of the connecting-rod

5, whereby motion is transmitted from the piston to the crank-shaft. The cylinder 1 and crank-case 2 are united to form a closed crank-chamber 6, having an inlet 7 and suitable outlets 8 and 9, the outlet 8 communicating with an auxiliary comparatively small cylinder 10 for the purpose presently described, and the outlet 9 is connected by the conduit 10' to an inlet-port 11 in one side of the cylinder 1 near the base of an interior explosion-chamber 12, said chamber being also provided with an exhaust-port 13, which is located diametrically opposite to the inlet-port 11.

In the preferred form or construction of this gas-engine the air under atmospheric pressure is admitted into the crank-chamber 6 through the inlet 7 and suitable conduit 14, having a check-valve 15 and a throttle-valve 16, the check-valve 15 serving to prevent back flow of the air from the crank-chamber and at the same time permitting the inflow of such air, and the throttle-valve 16 is for the purpose of controlling the quantity of air admitted to the crank-chamber. This air is drawn into the crank-chamber by suction or under the partial vacuum created by the upstroke of the piston 3 and is compressed in said chamber on the downstroke of said piston, and it is clearly evident that if a large volume of air is admitted by opening the throttle full open the effect of the compression of such air in the crank-chamber would be greater than if only a small quantity were admitted—that is, the pressure per unit area through the outlet 8 would be greater under the compression of a large volume than with a small volume for obvious reasons. It is therefore apparent that the throttle may be operated at will to control the degree of pressure per unit of area at the outlet 8, and this pressure is utilized to automatically operate a piston 17 which is movable in the auxiliary cylinder 10. This cylinder 10 is closed at the top or above the piston and is open at the base below the piston for communication with the outlet 8, so that the crank-chamber is always in communication with the auxiliary cylinder 10 to allow the free action of the compressed air from the crank-chamber against the piston and in this instance against its lower side or end. It is now clearly apparent that by closing the upper end of the cylinder 10 an air-chamber is formed, and the air in such chamber operates to partially resist the movement of the piston by the

pressure of air from the crank-chamber through the outlet 8, such resistance being further increased by a compression-spring 18, which is interposed between an adjustable shoulder 19 and piston 17.

It will be apparent from the foregoing description and upon reference to the drawings that the degree of movement of the piston 17 against the air-cushion in the upper end of the cylinder 10 and also against the action of the spring 18 will depend upon the degree of pressure per unit of area in the crank-chamber and its outlet 8. For example, if a large volume of air were allowed to enter the chamber 6 by opening the throttle-valve full open a maximum pressure would be produced in the chamber 6 on the downstroke of the piston 3, which would operate to produce a maximum movement of the piston 17 against the combined resistance of the spring 18 and air-cushion in the top of cylinder 10. On the other hand, if a small volume of air were admitted by throttling the entrance through the medium of the valve 16 a correspondingly light degree of pressure would be exerted in the crank-chamber and its outlet 8, and therefore the movement of the piston 17 would be comparatively light. If, now, this variable movement of the piston 17 be utilized to control the volume or quantity of liquid hydrocarbon which is to be admitted to the explosion-chamber, it is evident that when the compression of air per unit of area is greatest in the crank-chamber under a heavy load carried by the engine the piston 17 will be moved through a considerable distance, and therefore a heavy charge or maximum quantity of the liquid hydrocarbon will be forced into the explosion-chamber and exploded, thereby supplying the maximum power to meet the work required of the engine, while, on the other hand, if the engine is running light or slow and only a small quantity of the liquid hydrocarbon is required the throttle 16 is partially closed, so as to admit only a small quantity into the crank-chamber, thus allowing for only a slight compression and correspondingly light movement of the piston 17, which will force a correspondingly small quantity of the hydrocarbon liquid into the explosion-chamber, the effect of which, when expanded, is of course comparatively light in impelling the main piston 3 downward. In order to accomplish this automatic forced feed of the liquid hydrocarbon into the explosion-chamber, I provide the piston 17 with a depending plunger 20, which is movable in a subcylinder 21, the plunger 20 and part 21 constituting a force-pump; the interior of the cylinder 21 communicating with a passage 22, having one end connected to a liquid-hydrocarbon-supply-pipe 23 and its other end connected by a conduit 24 to a spraying-nozzle 25, which enters

the explosion-chamber in close proximity to 65 but slightly above the air-inlet port 11.

It will be observed upon reference to Fig. 1 of the drawings that the air and liquid carbon are forced into the base of the explosion-chamber at nearly the same point, but in intersecting paths, for the purpose of mixing at their points of entrance into the explosion-chamber, thereby avoiding any possibility of introducing an explosive mixture into any other part of the engine, and particularly the 70 crank-chamber, which receives only air.

The plunger 20 and piston 17 are limited in their downward movement by a shoulder 20', which is secured to the plunger 20 and engages the upper end of the cylinder 21 and 80 serves to close communication between the outlet 8 and interior of the cylinder 21, thereby preventing the entrance of air into the conduit 22 when the piston 17 is at its down-stroke or when the air-pressure within the 85 crank-chamber 6 is neutralized or overcome by the resistance-spring 18 and air-cushion above the piston 17, it being understood, however, that the lower end of the piston or plunger 20 terminates a slight distance above 90 the passage 22, so as to allow free communication between the conduits 23 and 24.

The passage-way between the conduit 23 and interior of the cylinder 21 is provided with a check-valve 26 to prevent back flow 95 of the liquid hydrocarbon, as gasoline, and the passage between the interior of the cylinder 21 and conduit 24 is also provided with a check-valve 27 to prevent back flow of the liquid hydrocarbon from the explosion-chamber, and it therefore appears that the chamber in which the plunger is movable communicates with the passage 22 between the check-valves 26 and 27.

In the operation of my invention thus far described the throttle-valve 16 is open to admit the desired amount of air to the crank-chamber, the amount of air depending upon the work required of the engine—as, for instance, if a heavy load is placed upon the engine the throttle is open to its full capacity, so that on the upstroke of the piston 3 the suction or partial vacuum produced in the chamber 6 draws the air into said chamber and into the space formed by the rise of the piston 3, and as the piston descends on its downstroke the check-valve 15 is automatically closed against the escape of air from the crank-chamber, and such air is therefore compressed in said chamber and is partially forced out through the outlet 8, thereby impinging and elevating the piston 17 against the action of the spring 18 and also against the air-cushion which is formed in the upper end of the cylinder 10. This elevation of the piston 17 causes a similar elevation of the plunger 20 and allows a certain quantity of the liquid hydrocarbon, as gasoline, to flow 110 115 120 125

upwardly into the interior of the cylinder 21 and into the conduit 22, and as soon as the piston 3 approaches the limit of its down-stroke sufficient to uncover the port 11 the 5 air under compression in the crank-chamber and conduit 10 is instantly forced into the base of the explosion-chamber, and simultaneously with this relief of the pressure in the crank-chamber and its outlet 8 the spring 18 10 and expansion of the compressed air in the upper part of the cylinder 10 operate to force the piston 17 downwardly with considerable force, thereby causing a similar and simultaneously downward movement of the 15 plunger 20, which expels the hydrocarbon liquid from the cylinder 21 and conduit 22 upwardly through the conduit 24 and nozzle 25 into the base of the explosion-chamber 12, where it is caused to mix with the inflowing 20 air in suitable proportions, such mixture being deflected upwardly by a deflecting-plate 29 on the head of the piston 3. It is now clear that both the air and liquid hydrocarbon enter the side of the explosion-chamber 25 at substantially the same point and under a high degree of pressure and that the quantity of liquid hydrocarbon which is caused to enter the explosion-chamber is proportionate to the pressure of the air in the crank-chamber by reason of the fact that this pressure of the air in the crank-chamber controls the amount of movement of the pistons 17 and 20. In order to further control the flow of the amount of liquid hydrocarbon which may 30 enter the explosion-chamber, I provide the shoulder 19 upon the adjusting-screw 30, which is movable in the upper end of the cylinder 10 and serves to produce more or less tension upon the spring 18, thereby affording 35 more or less resistance to the elevation of the piston 17 by the compressed air from the crank-chamber 6 on the downstroke of the piston 3.

I do not wish, however, to limit myself to 40 the use of the piston 17 and its spring 18 for operating the force-pump, as the plunger 20 and part 21, as any other equivalent pressure-regulating device may be employed to actuate any other form of plunger other than 45 that shown and described, and I would reserve the right to employ any device which may be operated by the compression of air in the crank-chamber and capable of forcing liquid hydrocarbon into any part of the explosion-chamber, together with any means for controlling the inlet of air into the crank-chamber at any point below the lower end of the piston, as 3, when in its extreme inner position or stroke. I have therefore shown 50 the upper portion of the crank-case as provided with an additional air-inlet 31, which is below the exhaust 13 and communicates with a conduit 32, having a throttle-valve 33, and when the air is admitted at this point the 55 lower throttle-valve 16 would be closed, so 60 that a vacuum would be created in the crank-chamber by the upstroke of the piston 3 until the lower end of the piston uncovered the air-inlet 31, at which time the air would instantly rush into the crank - chamber and 65 be compressed on the downstroke of the piston in the manner previously described. I have also shown the conduit 24 as provided with a two-way valve 34, to which is connected a second conduit 24', leading to a 70 spray-nozzle 25', which discharges into the upper end of the explosion-chamber 12 and may be substituted in operation for the inlet-nozzle 25, the valve 34 serving to connect the conduit 24 either to the nozzle 25 or 25', 75 but to only one at a time. When the nozzle 25' is used, the nozzle 25 of course is cut out, and the mixture of the air and liquid hydrocarbon is effected in the upper part of the explosion-chamber; but in either case the explosive mixture is compressed on the upstroke of the piston and ignited at the proper 80 time by suitable sparking device 35, Fig. 1.

What I claim is—

1. In a gas-engine of the class described, 90 the combination with an explosion-chamber and crank-chamber and a piston, the explosion-chamber having separate inlets, one for air and the other for liquid hydrocarbon, the air-inlet communicating with the crank-chamber, an air-supply conduit also communicating with the crank-chamber and provided with a throttle-valve for controlling the amount of air admitted to said crank-chamber, an outlet-conduit leading from the 95 crank-chamber, said piston compressing the air in the crank-chamber and its outlet on its downstroke, a movable member actuated in one direction by the compression of the air in said crank-chamber and outlet, means for actuating said member in the opposite direction when the pressure in the crank-chamber is relieved by the opening of the air-inlet-port and additional means brought into action by the reaction of said member to force liquid 100 hydrocarbon into the explosion-chamber.

2. In a hydrocarbon-engine, a cylinder, a crank-case and a piston, said cylinder having an air-inlet port connecting with the crank-chamber and also provided with a separate 115 inlet for liquid hydrocarbon, an air-supply conduit leading to the interior of the crank-chamber and means for graduating the air-supply to regulate the degree of pressure in the crank - chamber by the compression-stroke of the piston and means brought into action by said pressure from the crank-chamber for feeding hydrocarbon liquid through its port into the explosion-chamber, the 120 quantity of such liquid hydrocarbon which is fed to the explosion-chamber being proportionate to the air-pressure in the crank-chamber.

3. The combination with a gas-engine in which the air is compressed in the crank-chamber by the downstroke of the piston, of means for graduating the entrance of air into the crank-chamber thereby controlling the degree of pressure therein and separate means controlled by such pressure for feeding hydrocarbon liquid into the explosion-chamber of the engine.
10. 4. In a gas-engine, an explosion-chamber having an inlet-port for the liquid hydrocarbon and also provided with a chamber in which air is compressed by the piston, means for graduating the degree of pressure in said chamber and a feeding device for the hydrocarbon liquid controlled by such pressure whereby the quantity of the liquid hydrocarbon fed to the explosion-chamber is proportionate to the degree of pressure in said chamber.
15. 5. In a gas-engine, the combination of an explosion-chamber and a crank-chamber, a by-pass leading from the crank-chamber to the explosion-chamber, means for admitting and regulating the entrance of the air into the crank-chamber, such air being compressed on the downstroke of the piston, a movable element actuated by the pressure of air from the crank-chamber, a yielding resistance operating to return said element when the air-pressure is relieved and means actuated by the return of said element for forcing hydro-
- carbon liquid into the explosion-chamber of the engine.
20. 6. In a gas-engine the combination of a piston and air-chamber in which air is compressed by the said piston and means controlled by the pressure of air in said chamber for forcing liquid hydrocarbon into the explosion-chamber of the engine, said means including an air-operated element, a yielding resistance returning said element and a plunger actuated by said element upon its return to force the liquid hydrocarbon into said explosion-chamber.
25. 7. In a gas-engine, the combination of a piston and air-chamber in which air is compressed by the said piston and means controlled by the pressure of air in said chamber for forcing liquid hydrocarbon into the explosion-chamber of the engine, said means including an air-operating element, a yielding resistance returning said element and a plunger actuated by said element upon its return to force the liquid hydrocarbon into said explosion-chamber, and adjustable means for varying said yielding resistance.
30. In witness whereof I have hereunto set my hand this 11th day of May, 1905.

DANIEL M. TUTTLE.
